UNITED STATES PATENT OFFICE.

GEORGE H. RICH, OF CHICAGO, ILLINOIS.

COFFEE-SEPARATOR.

SPECIFICATION forming part of Letters Patent No. 451,236, dated April 28, 1891.

Application filed September 5, 1890. Serial No. 364,014. (No model.)

To all whom it may concern:

Be it known that I, GEORGE H. RICH, a citizen of the United States of America, residing at Chicago, in the county of Cook and State 5 of Illinois, have invented certain new and useful Improvements in Coffee-Separators, of which the following is a specification.

My invention relates to a machine primarily designed to separate the round beans found 10 in coffee from the flat ones, but also useful in separating and cleaning a variety of other articles where it is desired to separate the round from the flat grains. This machine is shown in its preferred form in the drawings 15 presented herewith, wherein—

Figure 1 is a plan view, and Fig. 2 a vertical longitudinal section in line 22 of Fig. 1.

The object of my invention is to attain greater speed in the separation of these articles, together with greater simplicity and effectiveness in the machine used therefor.

I shall first describe fully and specifically the machine which I have constructed for this purpose in its preferred form, and shall there- 25 after clearly point out and define the different improvements therein which I believe to be new and desire to secure by Letters Patent.

Applying reference-letters to the various parts of the machine in the two figures, A is 30 the frame, B the hopper which feeds the coffee to the machine, and C C' the boxes into which the different portions of the latter are delivered. To the lower portion of the frame A two upwardly-extending spring-arms D D are rigidly fastened, carrying upon their free 35 ends a swinging frame E. Two shafts F F' are journaled in the frame of the machine and two others G G' in the swinging frame. Each of the said shafts carries sprocket or rag wheels 40 g' f' f', upon which an endless apron H is carried by means of side chains h. The shafts F' G' run loosely in their respective frames; but the shaft F passes through the frame of the machine and carries outside thereof a sprocket- 45 wheel I. At the opposite end of the machine a shaft J is also journaled in the frame there- of, carrying at one end a pulley j, by means of which power is applied to rotate it, and at the other end a sprocket-wheel j', geared to 50 the wheel I by means of a chain K. This shaft is turned down upon a center offset from

its own axis to form eccentrics j^2 , which carry the arms L, extending to the swinging frame and rigidly fastened thereto. The portion of the endless apron H which extends between 55 the shafts G G' is supported so as to lie substantially straight by metal plates e, and arranged above this portion of the apron is the hopper B, containing a sliding gate b, adjustable up or down by means of the clamping- 60 screw S, and outside of this gate, near the bottom of the hopper, is arranged a feed-roller R, longitudinally corrugated about its periphery, mounted in the frame of the hopper and also of the machine (the two being rigidly 65 connected) upon a shaft r, bearing at its end a sprocket-wheel r' in position to engage with the chain K. Upon the frame E, also over the straight upper portion of the apron and at a distance therefrom sufficient to allow a 70 round bean to roll beneath, but not a flat one, is secured a board T. This board is inclined a trifle more than the apron, so that its upper edge is farther from the latter than its lower edge. This adds greatly to its effect- 75iveness in turning the beans upon their flat sides when they are beneath it. The frame E is so arranged that the said portion of the apron is inclined downward from the shaft G to the shaft G'. 80

The operation of this device is as follows: The coffee or other material is poured into the hopper B, passes therefrom beneath the gate b in quantities determined by the adjustment of the latter, is taken up by the feed-roller R, 85 and dropped upon the apron H. The latter is kept in continuous motion from the shaft G' to the shaft G by means of the sprocket-wheel f, driven through the gearing shown by the power-shaft J. At the same time the 90 frame E is vigorously shaken through the arm L by the eccentrics j^2 upon said power-shaft. Thus a continuous motion of the apron up the incline is attained, which of course tends to carry the material fed upon said 95 apron over into the box C. At the same time a vibratory movement of the upper portion of said apron is kept up, which tends to shake said material down over the inclined surface into the box C'. When any article like cof- 100 fee, composed of both flat and round particles, is fed upon this apron, the flat particles

tend to rest upon their flat sides and travel up the inclined apron in spite of the shaking of the latter, while the round particles, on the other hand, roll down said incline much more rapidly than the apron itself moves, and hence drop into the box C'. Whenever any of the flat beans strike upon their edges and in turning over gain sufficient momentum to go bouncing down the incline in spite of their flat shape, they will find it impossible to pass between the board T, for the latter is adjusted so as to leave barely room for the round beans to roll beneath it; but the space is not sufficient for the passage of the flat beans, as the latter pass down the incline by a series of bounds, leaving the surface of the apron at every jump. Moreover, as the round beans are invariably narrower (although thicker) than the flat beans, the board T can be so adjusted that the flat beans cannot pass beneath it, even though in rolling over they should remain in contact with the apron at all times. The portion of the apron carried by the vibrating frame E will ordinarily be kept taut by the weight of the lower loose portion of the apron. If, however, it should be found liable to displacement by the shaking of the frame, friction may be applied to the shaft F' to act as a sort of brake and resist the pull of the shaft F upon the apron.

The lower loose portion of the apron swings, as will be seen from the drawings, between the sprocket-shafts F F'. As these shafts are journaled in the frame of the machine, this portion of the apron will not partake of the vibratory movement of the frame E.

I claim—

1. In a machine of the class described, the combination, with the vibrating frame E, carrying the ascending endless apron H, of the board T, arranged as shown and being nearer to the apron at its lower edge than at its upper, substantially as described.

2. In combination with the frame of the machine, a feeding device and suitable driving mechanism, and a vibrating frame E, having the board T and carrying the ascending endless apron H, substantially as described.

3. In combination, the frame A, carrying the shafts F F', bearing the wheels I f f', the frame E, resting upon the spring-arms D D, carrying the shafts G G', bearing the wheels g g', the board T, the endless apron H, the shaft J, bearing the eccentrics j², the arm L, the chain K, and the hopper B, substantially as described.

GEORGE H. RICH.
